[57] ABSTRACT

A range control system is provided for a missile or projectile which utilizing its inflight prediction of the impact range error, provides means for correcting for this error. The system is carried in the vehicle, and it includes a comparator system which compares outputs from a vehicle-mounted accelerometer system with predetermined values. Any differences are fed to a function generator which produces a control signal. The control signal from the function generator operates a reaction control motor which, in turn, compensates for any variations of the vehicle from its course, so that the predetermined range of the vehicle is maintained.

Diagram illustrating a reaction control system (RCS) for a satellite, showing the control loop and associated components.

Key Components and Labels:

- Power Source:** 22
- Reaction Control Motor:** 22
- Power Amp.:** (Two stages)
- Logic Gates:** D1, D2
- Operational Amplifiers:** A1, A2, A3, A4, A5, A6
- Accelerometer:** Axial Accelerometer
- Time Variables:** $t \leq t_c$, $t > t_c$
- Feedback Path:** Accelerometer output $\ddot{Y}_2$ feeds into A3, A4, and A5.
- Control Path:** A6 provides a reference signal to A3, A4, and A5.
- Output Signals:** $+E_2$, $+E_3$, $+E_4$, $+E_5$, $+E_6$, $-E_4$, $-E_5$, $-E_6$, $+E_{12}$, α
- Timing:** A clock signal triggers the logic gates D1 and D2.

TACTICAL MISSILE RANGE CONTROL SYSTEM

BACKGROUND OF THE INVENTION

As is well known, if a projectile departs from its course at any time during its flight, these departures will affect the preset range of the vehicle and cause it to depart from its predetermined impact point. Even in the case of guided missiles, if the vehicle leaves its predetermined course, there is a variation in gravity acceleration which produces errors in the data programmed into the guidance system. The vehicle-mounted range control system of the present invention provides a low cost means of achieving range control for battlefield and other tactical missiles and projectiles. The system provides for the vehicle to be held at all times on its predetermined course, so that its established range is accurately and precisely maintained.

BRIEF DESCRIPTION OF THE DRAWINGS

FIG. 1 is a schematic representation of a projectile or missile, and showing in block form a control system incorporating the concepts of the invention, the control system being represented as mounted within the vehicle;

FIG. 2 is a more detailed block diagram of a range control system representative of one embodiment of the invention; and

FIG. 3 is a schematic circuit diagram of the system shown in block diagram of FIG. 2.

DETAILED DESCRIPTION OF THE ILLUSTRATED EMBODIMENT

In FIG. 1, the missile or projectile is represented as 10, and the control system representative of one embodiment of the invention, and which is mounted within the vehicle 10 is shown, as mentioned above, in block form. The system of FIG. 1 includes, for example, an accelerometer 12 which is designated an "axial accelerometer," and which is mounted with its sensitive axis coincident with the vehicle longitudinal axis. The system also includes a comparator system designated by the block 14 and which, as will be described, and as shown in FIG. 2, includes three integrators 16, 18 and 20. The integrator 20 provides a track and hold function; and the integrators 18 and 16 serve for doubly integrating the output of the axial accelerometer 12.

The control system also includes a small reaction control rocket motor 22, or equivalent device, which is aligned with its thrust axis perpendicular to the center line of the vehicle 10 and in a vertical plane. A clock or timer circuit 24 is provided for controlling the sequence of the system. It is assumed that the vehicle incorporates the usual system for maintaining its roll orientation relative to the vertical, and such a system is not shown.

As shown in FIG. 1, the output from the comparator system 14 is fed to a function generator 26 whose output is applied to a zero detector system 28 which, in turn, controls the reaction control motor 22. As shown in FIG. 2, the zero detector system 28 includes a zero detector number 1, and a zero detector number 2, the outputs from the zero detectors number 1 and 2 being passed through an "and" gate 30 to the reaction control motor 22.

As will be described, the vehicle 10 is maintained on its predetermined course by controlling the length of

time the reaction control motor 22 is operated. This control is obtained by comparing the actual readings derived from the accelerometer 12 with calculated readings, and by feeding the difference into the function generator 26. The function generator 26 then provides the control signal for the reaction motor 22.

As shown in more detail in FIG. 2, the clock circuit 24 controls three single-pole double-throw relay switches designated Y1, Y2 and Y3. When these switches are in their down position, the system is controlling. However, when the clock circuit moves the switches to their upper position, the output from the axial accelerometer 12 is integrated first in the integrator 18 so that the accelerations are transformed into velocities (v), and the output from the velocity integrator 16 is integrated by the integrator 20 so that the velocities are transformed into arc lengths (s).

At the same time, the accelerometer track and hold integrator 20 is connected to the output of a comparator circuit 50, the inputs of which are connected to the output of the accelerometer 12 and to the output of the integrator 20. The output (a) from the integrator 20 is also applied to a comparator circuit 52 in which it is compared with a predetermined nominal acceleration value (a_0).

Likewise, the output (V) of the integrator 18 is applied to a comparator 54 in which it is compared with a predetermined nominal value (v_0), and the output of which is applied to a gain K_v . The output (s) of the integrator 16 is applied to a comparator 56 in which it is compared with a predetermined nominal value (s_0), and the output is applied to a gain K_s . The outputs of the gain K_A , K_v and K_s are all applied to a summing network 58, and the output δR of the summing network 58 is applied to the function generator 26.

The output of the clock circuit (t) is applied to a comparator 60 in which it is compared with a predetermined time (t_B) and the output of the comparator 60 is applied directly to the zero detector No. 1 and to a summing network 62. The output (Δt) of the function generator 26 is applied to the summing network 62, as is a predetermined value (T_0). The output of the network 62 is applied to the zero detector No. 2.

Although the various components designated above will be shown and described in somewhat more detail in FIG. 3, it should be pointed out at this time that the individual components such as the clock circuit 24, the axial accelerometer 12, the integrators, the function generator 26, the summing networks, the comparators, the zero detectors, the "and" gate 30 and the reaction control motor 22 are all well known to the art, so that a detailed description of these individual components is deemed to be unnecessary.

In the operation of the system of FIG. 2, any departures of the vehicle 10 from its flight path will produce error signals, and these error signals will cause the time histories of the outputs from the accelerometer 12, and will cause the outputs of the integrators 18, 16 and 20 to differ from certain predetermined nominal values (v_0), (s_0) and (a_0) respectively. At some time (t_c) during the flight the clock circuit 24 operates the relay switches Y1, Y2 and Y3 to establish the input of the three integrators 16, 18 and 20 at a reference level so that the outputs of the three integrators remain constant thereafter. At this point, the three constant values of the three integrators, namely s , v and a are compared

in the respective comparators 56, 54 and 52 with their respective nominal values s_o , v_o and a_o .

The three difference outputs from the comparators 56, 54 and 52 are linearly combined in the summing network 58 to provide an estimate of the error that would occur if no correction were made. This error is designated δR . In order to effectuate the correction, the small reaction motor 22 is utilized. As mentioned above, the reaction motor 22 is oriented with its thrust axis in a vertical plane and normal to the center line of the vehicle 10. The direction of thrust of the reaction control motor 22 is generally upward.

Independent of the aforesaid in-flight estimate of range error, the motor 22 begins to fire at a predetermined time (t) during the flight if the range error is estimated at zero. That is, if the estimate shows that the vehicle is on its correct course towards the target, then the motor 22 burns for a duration of T_o seconds. If the estimate is that the vehicle will fall short of the target, the duration of the burn of the motor 22 is extended for ΔT seconds, where ΔT is a function of the estimated range error as derived from the function generator 26. This function is determined in the function generator by simulation and in most cases will turn out to be a simple proportionality. If, on the other hand, the estimate is that the vehicle will overshoot the target, the duration of the burn of the motor 22 is shortened by a period of time (ΔT) which is, again, the same function of estimated range error.

The implementation of the foregoing is achieved, for example, by the system of FIG. 2 in which the output of the accelerometer 12 is fed to the integrators 16, 18 and 20 through the aforesaid integrator for said relay switches Y1, Y2 and Y3. The output (a) from the integrator 20 is fed back to its input through the comparator 50 form a "track and hold" circuit. The output (v) of the velocity integrator 18 is fed through the relay switch Y1 to the integrator 16 to provide the arc length data (s). The three relay switches Y1, Y2 and Y3 are actuated by the clock 24 which serves as a timer to control the entire process. It is pointed out that the relay switches Y1, Y2 and Y3 may be solid state type switches, rather than electromagnetically operated relay switches, if so desired.

The respective outputs s , v and a are compared in the summing or comparator networks 56, 54 and 52 with the respective nominal values s_o , v_o and a_o , and the coefficients of combination, that is the gains K_s , K_v and K_a are determined using a so-called static Kalman filter, or linear regression, technique, as designated by the blocks K_s , K_v and K_a .

At a pre-selected observation time (t_c) the clock 24 causes the three switches Y1, Y2 and Y3 to establish the three integrator inputs 16, 18 and 20 at a reference level, as mentioned above, and this in turn causes their outputs to hold at their values at the time t_c . The three outputs from the integrators, summed as described above, are then fed to the function generator 26 which represents the time (ΔT) required, as a function of the estimated range (δR).

Time (t) generated electrically by the clock 24 is compared in the comparator 60 with a predetermined time (t_B), at which the burn of the reaction control motor 22 is to commence. When the differential between t and t_B becomes positive, the output (Q_1) of the zero detector No. 1 changes from "0" to "1," so as to enable the "and" gate 30. The differential ($t-t_B$) is ap-

plied to the zero detector No. 2 by the summing network 62, where it is subtracted from the sum $T_o + \Delta T$. Normally, $|\Delta T| < T_o$, so that $T_o + \Delta T$ is positive. Thus, when $t-t_B \leq 0$, the net input to the zero detector No. 2 is positive, and its output Q_2 is a "1." As $t-t_B$ becomes more positive, a point is finally reached when $t-t_B \geq T_o + \Delta T$. At this time, the required burn time of the motor 22 has ended, and the input to the zero detector No. 2 goes negative, setting Q_2 to "0."

The signals Q_1 and Q_2 are fed to the "and" gate 30 whose output controls the reaction control motor 22. When $Q_1 = Q_2 = 1$, the motor 22 burns. Otherwise, it is inoperative. The operation of the reaction control motor may be summarized by the following table:

		Q_1	Q_2	Reaction Control Motor 22
$t - t_B < 0$		0	1	Off
$0 \leq t - t_B < T_o + \Delta T$		1	1	On
$t - t_B \geq T_o + \Delta T$		1	0	Off

As illustrated in FIG. 3, the block diagram of FIG. 2 may be implemented, for example, by operational amplifiers A1-A9, connected as shown. The "and" gate 30 is formed, for example, by a pair of diodes D1 and D2, and a power amplifier A8 is interposed between the "and" gate and the reaction control motor 22. The operational amplifiers A1, A3 and A4 form the integrators 16, 18 and 20 respectively.

The invention provides, therefore, a low cost control system capable of providing accurate in-flight range controls for tactical missiles. It will be appreciated that although a particular embodiment of the invention has been shown, alternate mechanizations are possible. For example, a differential digital analyzer (DDA), or other digital means may be used to implement the foregoing integrations and computations. Moreover, the rocket motor 22 may be replaced by fins, or other steering means for the vehicle. Also, for more inexpensive systems, one or more of the integrators 16, 18, 20 may be omitted, although this would result in a concomitant degradation of system performance. Alternately, additional sensors and/or integrators may be incorporated to enhance system performance.

Therefore, although a particular embodiment of the control system of the present invention has been shown and described modifications may be made. It is intended to cover all modifications which fall within the scope of the invention in the following claims.

APPENDIX

Derivation of Estimator

The following linear regression, or static Kalman filter technique, represents a method which may be used to determine the estimating gains K_a , K_v and K_s .

First consider the three integrator outputs a , v and s as an observation vector $\underline{y}$:

$$\underline{y} = (a, v, s)$$

The vector $\underline{y}$ can be related to a vector of error sources, $\underline{\epsilon}$, and a measurement noise vector, $\underline{v}$, by

$$\underline{y} = H \underline{\epsilon} + \underline{v}$$

where: H is a Jacobian matrix (of partials) of the form

$$H = [\delta Y_i / \delta \epsilon_j], i = 1, 2, 3; j = 1, \dots, n$$

where $\underline{\epsilon}$ is an n -dimensional vector of the form

$$\underline{\epsilon} = [\epsilon_1, \epsilon_2, \dots, \epsilon_n]$$

The error sources $\epsilon_1, \dots, \epsilon_n$ include the contributors to range error, such as

1. initial velocity
2. weight
3. drag coefficient
4. total impulse
5. range winds.

We may also write the on-target range error, ϵ_R , as:

$$\epsilon_R = \underline{\phi}' \underline{\epsilon}$$

where ('') indicates transpose and $\underline{\phi}'$ is a row vector of the form:

$$\underline{\phi}' = [(\delta \epsilon_R / \delta \epsilon_1) (\delta \epsilon_R / \delta \epsilon_2) \dots (\delta \epsilon_R / \delta \epsilon_n)]$$

It is desired to estimate, from the observation $\underline{y}$, the on-target error, ϵ_R . If this estimate is to be a linear function of $\underline{y}$, then we can write the estimate as,

$$\hat{\epsilon}_R = \underline{k}' \underline{y}$$

where: $\hat{\epsilon}_R$ is the estimate of ϵ_R and $\underline{k}'$ is the row vector of gains $[K_A, K_V, K_S]$.

The error in the estimate is:

$$\tilde{\epsilon}_R = \epsilon_R - \hat{\epsilon}_R$$

The criterion for selecting the gain vector, $\underline{k}$, is a least square error criterion. The expectation of the square of the error is given by

$$E [\tilde{\epsilon}_R^2] = E [(\epsilon_R - \underline{k}' \underline{y})^2]$$

To minimize this function with respect to $\underline{k}$, we take the gradient of $E [\tilde{\epsilon}_R^2]$:

$$\text{grad}_{\underline{k}} E [\tilde{\epsilon}_R^2] = -2E [(\epsilon_R - \underline{k}' \underline{y}) \underline{y}]$$

Setting this equation to zero gives:

$$E [(\epsilon_R - \underline{k}' \underline{y}) \underline{y}] = 0$$

Expanding:

$$E [\epsilon_R \underline{y}] - E [(\underline{k}' \underline{y}) \underline{y}] = 0$$

$$E [\epsilon_R \underline{y}] - E [\underline{y} (\underline{k}' \underline{y})] = 0$$

$$E [\epsilon_R \underline{y}] - E [(\underline{y} \underline{y}') \underline{k}] = 0$$

Define

$$E [\underline{y} \underline{y}'] = C_{yy} ; E [\epsilon_R \underline{y}] = C_{\epsilon y}$$

Then,

$$\underline{k} = C_{yy}^{-1} C_{\epsilon y}$$

$$C_{yy} = E [\underline{y} \underline{y}'] = E [(H \underline{\epsilon} + \underline{y}) (H \underline{\epsilon} + \underline{y})']$$

$$C_{yy} = E (H \underline{\epsilon} \underline{\epsilon}' H') + E [\underline{y} \underline{\epsilon}' H'] + E [H \underline{\epsilon} \underline{y}'] + E [\underline{y} \underline{y}']$$

Since $\underline{y}$ and $\underline{\epsilon}$ are independent,

$$E [\underline{y} \underline{\epsilon}' H'] = E [H \underline{\epsilon} \underline{y}'] = 0$$

Then:

$$C_{yy} = H E [\underline{\epsilon} \underline{\epsilon}'] H' + E [\underline{y} \underline{y}']$$

Let:

$$C_e = E [\underline{\epsilon} \underline{\epsilon}'] ; C_v = E [\underline{y} \underline{y}']$$

We have:

$$C_{yy} = H C_e H' + C_v$$

Now,

$$C_{\epsilon y} = E [\epsilon_R \underline{y}] = E [\epsilon_R H \underline{\epsilon}] + E [\epsilon_R \underline{y}]$$

$$\text{Since } \epsilon_R \text{ and } \underline{y} \text{ are independent, } E [\epsilon_R \underline{y}] = 0 \text{ and } C_{\epsilon y} = E [\epsilon_R H \underline{\epsilon}] = E [(\underline{\phi}' \underline{\epsilon}) H \underline{\epsilon}] = E [H \underline{\epsilon} \underline{\phi}' \underline{\epsilon}]$$

$$C_{\epsilon y} = H C_e \underline{\phi}$$

10 Substituting these results into the expression for $\underline{k}$ gives:

$$\underline{k} = [H C_e H' + C_v]^{-1} H C_e \underline{\phi} = (K_A, K_V, K_S).$$

In mechanizing this system, we denote $\hat{\epsilon}_R = \delta \hat{R}$, and 15 we have:

$$\delta \hat{R} = \underline{k}' [a, v, s]$$

where:

$$\underline{k} = (K_A, K_V, K_S) = [H C_e H' + C_v]^{-1} H C_e \underline{\phi}$$

What is claimed is:

1. A vehicle-mounted range control system for a missile, projectile, or other vehicle comprising:
25 accelerometer means mounted on the vehicle with its sensitive axis coincident with the longitudinal axis of the vehicle and having an output at which electrical signals representative of accelerations of the vehicle in the direction of said longitudinal axis are produced;
a first and second integrator each having an input and an output;
a first switch having a first position for coupling said first integrator to the output of said accelerometer and a second switch having a first position for coupling the input of said second integrator to the output of said first integrator;
comparator means coupled to the output of said integrators for comparing the output therefrom with predetermined nominal values;
40 a third integrator arranged as a track and hold circuit having an input and an output, with said output being coupled to said comparator means;
a third switch having a first position for coupling the input of said third integrator to said accelerometer and a second position for coupling said third integrator input to a point of reference potential;
a course control unit for the vehicle; and
function generator means coupled to said comparator means and responsive to the outputs therefrom for controlling the operation of said course control unit.

55 2. The range control system defined in claim 1, in which each of said first and second switches includes a second position for coupling the inputs of said first and second integrators to a point of reference potential, and which includes a clock timing circuit for actuating said first, second, and third switches selectively to their first and second positions.

60 3. The range control system defined in claim 1 in which said first integrator produces output signals representative of the velocity of the vehicle along the longitudinal axis, said second integrator is selectively coupled to said first integrator for producing output signals representative of the arc length of the vehicle along its flight path, said third integrator produces track and hold output signals representative of the vehicle acceleration, and further including a summing circuit re-

sponsive to the output signals from the three integrators.

4. The range control system defined in claim 3, and which includes a clock timer circuit coupled to said switches for selectively coupling the inputs of said integrators to said accelerometer means for a certain time interval, and for then coupling the inputs of said integrators to a point of reference potential.

5. The range control system defined in claim 4, and which includes zero detector circuit means interposed

5 10 between said function generator means and said course control unit, and further comparator means interposed

between said clock timer circuit and said zero detector

circuit means for establishing a predetermined time in-

terval at which said course control unit is to be acti-

vated.

6. The range control system defined in claim 1, in which said course control unit comprises a reaction control rocket motor.
